MULTIPLE SPINDLE CHUCKING MACHINE

Arthur J. Lewis, Stratford, Conn., assignor to The
Baird Machine Company, Stratford, Conn., a
corporation of Connecticut

Application November 18, 1942, Serial No. 466,011

51 Claims. (Cl. 29—38)

1

This invention relates to a multiple spindle chucking machine, and has for an object to provide a machine in which machining operations may be performed on both ends of a work piece, as for example a cartridge shell or casing, in a single chucking operation.

Another object is to provide a construction in which the various operations are performed during one revolution of the turret carrying a plurality of work spindles, so that although several work pieces are operated upon and finished during each revolution of the turret the operations for a single piece require a greater part of a single revolution of the turret, and thus the cutting, turning, drilling, or other operations may be performed at the desired lower speeds to secure best operation and maximum life of the tools.

Another object is to provide a construction in which the number of different operations are automatically performed in certain timed relation with each other during the revolution of the turret.

A further object is to provide a construction in which the operations are so performed that the turret may be rotated continuously and operated at a sufficiently low speed to permit loading and unloading of the work carrier or the chucks while the turret is rotating, doing away with the necessity of stopping and starting the turret for loading and unloading each work piece, eliminating indexing operations and consequent necessary indexing mechanism, and materially increasing production.

A further object is to provide a construction in which the work piece is automatically properly located in the chuck prior to closing or gripping of the chuck, and after the operations have been completed the chuck is automatically opened or released and the work piece is ejected or shifted to a position where it may be readily grasped by the operator and removed.

A still further object is to provide a construction in which there is a constantly rotating turret in which is mounted a plurality of work-carrying spindles, and in which the spindles are continuously rotated during the working operations and during a greater part of the rotation of the turret, and are stopped only for the removal of the finished work piece from and the insertion of an unfinished piece in the chuck.

Another object is to provide a construction in which a number of different types of operations may be performed on the work piece during a cycle or a single revolution of the turret.

Still another object is to provide a construction

2

in which a plurality of operations are performed on a work piece which may require a plurality of different tools carried by different carriers, and in which one carrier may be automatically advanced to the working position and the tool fed for the working operation while the other carrier is locked in the retracted or inoperative position, and after the work of the tool or tools on this first carrier is completed it is automatically shifted to the retracted or inoperative position and locked while the second carrier is automatically unlocked and advanced and its tool or tools fed for their work operations.

With the foregoing and other objects in view I have devised the construction illustrated in the accompanying drawings forming a part of this specification. It is, however, to be understood the machine is not limited to the specific construction and arrangement shown, but that various changes and modifications may be employed within the scope of the invention.

In these drawings:

Fig. 1 is a top plan view of the machine;

Fig. 2 is a rear elevation;

Fig. 3 is an end elevation looking toward the right end of the machine or the top of Fig. 1;

Fig. 4 is a vertical section through the left-hand end of the machine and through one work spindle in the uppermost position, which is the position just after the work piece has been inserted in the chuck and just before the chuck closes, the central shaft being shown in elevation;

Fig. 5 is a section through the same spindle on a somewhat enlarged scale and showing a slight modification of the chuck and the trimming tool and with the chuck closed preparatory to starting of the operations on an unfinished work piece;

Fig. 6 is a section of the mounting and the drive for the trimming tool, it being a continuation of Fig. 5 toward the left;

Fig. 7 is a vertical section through the upper part of the right-hand end of the machine, showing the mounting and operating mechanism for the tools operating on the outer end of the work piece, the right-hand portion of the central shaft being shown in elevation;

Fig. 8 shows a work piece in a series of sectional views, together with the various tools shown diagrammatically in elevation, to indicate by way of example a number of operations which may be performed on this machine, and the sequence of these operations;

Fig. 9 is a top plan view of a portion of the mechanism for operating the trimming and knockout devices;

Fig. 10 is a transverse section thereof, substantially on the line 10—10 of Fig. 9;

Fig. 11 is a transverse section immediately in front of the outer ends of the work spindle, showing various turning and finishing tools in different positions throughout the revolution of the turret, the section being substantially on line 11 of Fig. 7;

Fig. 12 is a transverse section showing the operating means for the tools of Fig. 11, the section being on line 12 of Fig. 7, and in some of the positions the collet or chuck release lever being omitted;

Fig. 13 is a side elevation of the cam operated lever for the collet or chuck release which is carried by each of the tool-operating levers of Fig. 12;

Fig. 14 is a transverse section showing in elevation the feed mechanism for other tools, and indicating the different angular positions of these tools throughout a cycle or single revolution of the turret, the section being substantially on line 14 of Fig. 7;

Fig. 15 is a vertical transverse section through the tool carriers operated by the levers of Fig. 14 showing the tool carriers in the corresponding positions, the section being substantially on line 15 of Fig. 7;

Fig. 16 is a vertical transverse section showing the means for swinging the tool carriers of Figs. 14 and 15 to the different angular positions, and showing them in the positions corresponding to Figs. 14 and 15, the section being substantially on line 16 of Fig. 7;

Fig. 17 is a transverse section through a work spindle just back of the forward bearing and showing the lever for operating the collet or chuck release, the section being substantially on line 17—17 of Fig. 5;

Fig. 18 is a development of the trimming and knockout cam;

Fig. 19 is a partial side elevation and partial section of a portion of the cam of Fig. 18, the section being substantially on line 19—19 of Fig. 18;

Fig. 20 is a plan view of a development of the feed cam for the tools operated by the mechanisms of Figs. 14, 15 and 16;

Fig. 21 is a development of the collet or clutch release cam;

Fig. 22 is a work diagram showing the various operations of the machine illustrated and their relative timing with respect to each other;

Fig. 23 is a partial section and partial elevation of a device for automatically locating a work piece in proper position in the chuck, and

Fig. 24 is an elevation looking from the right of Fig. 23.

General arrangement

The machine comprises a frame or base 1 and a central main shaft 2 mounted to rotate in suitable bearings 3 and 4 in left and right hand end housings 5 and 6 respectively, mounted on the base 1. The left hand end housing 5 also provides a housing for the main drive for the central shaft 2. This drive comprises a worm gear 7 secured to the shaft 2 by any suitable means, such as for example as screws 8, and meshes with a worm 9 mounted on a shaft 10 in the upper part of the housing 5 operated by a drive pulley 11 through belts 12 running from one or more grooved pulleys 13 on the armature shaft of the motor 14, mounted on the housing 5. In the present case the end of the housing is covered and enclosed by a cap 15, and the motor 14 is mounted on a

bracket 16 pivoted to the cap at 17 about which the bracket may be swung through adjusting screws 18 to vary the tension of the belts.

As shown more clearly in Figs. 4 and 5, mounted on the central shaft 2 to turn therewith is a turret 19, in which turret is mounted a plurality of work-carrying spindles 20, in the present case there being five of these spindles. These are hollow spindles rotating in suitable antifriction bearings 21 and 22 in the turret. Each spindle is driven or rotated by a grooved pulley 23 mounted on the spindle, this pulley being driven by a series of V-belts 24 through a grooved pulley 25 on the armature shaft of an electric motor 26 (Figs. 1, 2 and 3). These belts also run over an idler pulley 27 which lifts the belts from the spindle pulleys 23 during a portion of their movement with the rotating turret, to permit stopping of the spindles for the unloading and loading operations, as will later be more fully described. The motor is mounted on a bracket 28, and the idler pulley 27 is mounted on a bracket 29 (Figs. 3 and 11) pivoted to bracket 28 at 30. A spring 31 on a rod 32 tends to swing the pulley 27 outwardly or to the left as shown in Figs. 3 and 11, to keep the belts 24 taut and at the proper tension, as well as to carry them away from the spindle pulleys 23 at the proper time.

Also mounted on the main shaft 2 to rotate therewith is a housing 33 (Figs. 1, 2, 4 and 6) carrying the trimming tools 34 and 34a (Figs. 4, 5 and 8) and the slide 35 therefor, there being one of these tools in alignment with each work spindle 20 to the rear of the turret and the work

spindles carried thereby.

At the opposite and forward side of the turret 19 and the work spindles is a barrel 36 (Figs. 1, 2 and 7) also mounted on the main shaft 2 to rotate therewith, and this barrel carries a number of different tools mounted and operated to be brought into position to perform various operations on the work piece carried by the individual work spindles, there being one set of these tools for each spindle carried around with the spindle as the turret rotates, so that these work operations are performed during the rotating movement of the turret, as will be more fully described later. Thus, the main shaft 2 through its rotation rotates the turret 19 carrying with it the work spindles, and the tools carried by the housing 33 for performing certain operations on one end of the work piece also rotate with the shaft 2 and therefore the turret 19, and the barrel 36 carrying the tools for performing the work operations on the other end of the work piece also rotate with the shaft 2 and the turret. The turret can therefore be rotated continuously through rotation of the main central shaft 2, and as the various tools are also mounted on this shaft and rotate with it they are carried around with the turret and the work spindles, so that all the various operations on the work piece are performed during rotating movement of the turret, and it is therefore not necessary to stop the turret with the work spindles at different working stations and to index the turret between these positions to bring the work to the various tools. It is therefore possible to operate on the work pieces during the greater part of a single revolution of the turret, thus making available all the time required for this portion of the revolution of the turret for performing the various operations on the work piece, permitting these operations to be performed at lower and more appropriate speeds, and assuring longer

life to the tools. As there are a plurality of spindles on the turret and therefore the various operations are being performed on a number of different work pieces simultaneously, a work piece is finished on each spindle during each revolution of the turret, thus greatly increasing production without increasing operative speeds on the work piece.

Work carrying spindles

As indicated above, the work-carrying spindles 29 (Figs. 4 and 5) are hollow spindles mounted to rotate in suitable bearings 21 and 22 in the turret 19 carried by the main shaft 2. Any desired number of spindles may be mounted in the turret (in the present case five are shown) and all the spindles are alike. Mounted within each spindle is a work-holding chuck comprising a collet 37 having jaws 38 to grip the work piece, in the present case a cartridge shell or casing 39 or 39a. The outer surfaces of these jaws are tapered, as indicated at 40, to cooperate with a similar taper 41 on the inner side of a sleeve 42, slidable longitudinally within the spindle. The collet 37 is secured at its inner end in the body portion of a sleeve 43, it being threaded into the sleeve, as shown at 44. This sleeve has a flange 45 seated against the rear wall of the web of the pulley 23, and the spindle 29 is threaded into the hub of this pulley, as indicated at 46.

The sleeve 42 is slidable longitudinally within the spindle 29 to clamp and release the chuck jaws 38 of the collet 37, the clamping being effected by taper 41 on the inner side of the sleeve having a camming action on the taper 40 on the jaws, the collet 37 being slit longitudinally between the jaws to permit the jaws to move inwardly and outwardly. The jaws tend to move outwardly through spring action of the shanks or connecting portions 47 of the collet, which are integral with the opposite continuous end portion 48 of the collet. A series of springs 49 are mounted in the recessed rear side of the pulley 23, each being anchored at its outer end by a pin 50 (Fig. 4) in the web of the pulley and a clamp ring 51 secured to the pulley flange by suitable screws (not shown). The inner free ends of the springs are each located in a radially extending recess or notch 52 in the flange 45 and press against a longitudinally slidable pin 53 mounted in the sleeve 43. These pins 53 rest at their opposite ends against the end of the sleeve 42 whereby the springs 49 tend to shift the sleeve 42 to the right as viewed in Figs. 4 and 5, and thus through the camming action of the tapers 40 and 41, serve to clamp the chuck jaws 38 against the work piece 39 or 39a.

The sleeve 42 may be shifted to the left or in the opposite direction to release these jaws and thus release the work through action of a series of pins 54 seated at their reduced inner ends in sockets in the sleeve 42 and carried by a ring 55 slidable longitudinally on the outer side of the spindle 29. Pins 54 pass through elongated slots 56 in the spindle so that the sleeve and pins may move relatively to the spindle. Embracing the ring 55 is a collar 57 which abuts at its rear edge against the shoulder 58 on the ring 55 so as to shift this ring to the left on shifting movement of the collar. The collar 57 does not rotate but the ring 55 rotates in this collar with the spindle. As shown in Fig. 17, the collar has recesses 59 in its opposite sides in which are seated lugs 60 on a U-shaped lever 61 pivotally

supported on pivot pins 62 mounted in the turret 19. The lever is engaged at its lower end by a collet or chuck release rod 63 (Figs. 4, 5 and 7), operated by suitable mechanism in certain timed relation with the work unloading and loading operations, as will later be more fully described. Suitable seals 64 may be provided at opposite ends of the spindle to retain the lubricant in the turret for the spindle bearings.

- 10 It will be seen from Figs. 4 and 5 that the inner end portion 48 of the collet forms a supporting means for the inner end portion of the work piece 39 or 39a, in the present case the shell or casing, and thus supports this end of the work piece properly concentric with the axis of rotation, the outer end being similarly supported and positioned by the collet or chuck jaws 38. For the shorter shell 39, as shown in Fig. 5, this portion 48 of the collet embraces the reduced portion 65, while in Fig. 4 where a longer work piece or shell is being operated upon it embraces and supports the body portion of the shell and an additional end support 66 is provided carried in a cap 67 mounted in the sleeve 43 so as to rotate with the spindle. In the holder for the shorter work piece of Fig. 5, the support 66 is omitted and the cap 68 has an enlarged opening therethrough to permit entrance of the trimming tool 34a for trimming the end of the work piece. If desired, a belt guard 69 may be mounted on the turret.

In the present machine a trimming operation is performed on the inner or left hand end of the work piece, that is the shell casing 39 or 39a, but it will be understood that with different work pieces different operations may be performed. The trimming tool is shown at 34 (Fig. 4) for the longer shell 39a, and the similar tool 34a (Fig. 5) for the shorter shell 39. The tool 34 is mounted on a tool holder 70, while the tool 34a is mounted in a similar holder 71, but this latter holder is extended and made longer so as to carry the tool 34a further into the spindle to engage the shorter work piece 39. The holder 70 and 71 is carried by a tubular slide 35 mounted to slide longitudinally in suitable bearings 72 and 73 in the housing 33 mounted on the shaft 2, so that this housing turns with the turret and maintains the trimming tool carriers in alignment with the respective spindles, it being understood there is a tool slide 35 for each spindle. Means for shifting this tool slide to carry the tool to and from the working position and feed it forwardly during the working operation is shown in Figs. 4, 6, 9 and 10. Mounted on the tube 35 forming the slide is a block 74 forming a carrier for a catch lever 75. The block is clamped to the slide 35 by any suitable means, in the present case it being split at 76 and clamped by a screw 77. This block or carrier includes an extension 78 carrying a bearing 79 slidable on a guide pin 80 mounted in the housing 33. This guide pin prevents the block or carrier from turning and therefore prevents the slide 35 from turning under action of the tool carried by it. Relative turning movement between the slide 35 and block or carrier 74 is prevented by clamping of the carrier on the slide. Mounted on the block 74 is an adjusting screw 81 having a cylindrical head seating in a notch 82 in one side of the slide 35. By loosening the screw 77 and adjusting the screw 81 the position of slide 35 in the carrier 74 can be adjusted, and then clamped in the adjusted position by tightening the screw 77.

75 Mounted on the lower side of the carrier 74 is

a roller 83 running in a cam groove in a cam 84 mounted on the end housing 5. A development of this cam is shown in Fig. 18 and the cycle of operations controlled by this cam and their relation to the other operations of the machine is shown by the outer circle 84a of Fig. 22. The catch lever 75 carries a roller 85 running on the outer cylindrical surface of the cam 84, but this surface is provided with a recess 86 extending throughout a certain portion of the periphery of this cam to permit the roller 85 to drop into it at a certain given time and permit the other end 87 of the catch lever, which is located in an opening 88 in the slide 35, to enter an annular groove 89 in a work ejector or knockout tube 90, to thus lock the block or carrier 74 to this tube 90 so that the tube at this time will move with the carrier. The opening 88 is an elongated opening, permitting relative movement between the carrier and the slide in adjusting the position of the slide in the carrier. The catch lever 75 is pivoted to the carrier 74 by the pin 75a, and the roller 85 is pressed against the cam 84 by a spring 75b mounted on the carrier.

Mounted in the housing 33 at the forward side of the carrier 74 is a bumper pin 91 projecting into the path of movement of the carrier and held in this position by a bumper spring 92, this pin being slidable in the housing and forming a spring bumper to assist in arresting forward movement of the carrier and associated parts on the ejector or knockout operation of the work piece, as will later be more fully described. The shank 93 of the pin is slidable in a plate 94 mounted in the housing and forming a stop for the nut 95 mounted on the shank to limit inward movement of the pin 91, and this plate 94 also forms an abutment for the spring 92.

The ejector or knockout tube 90 is mounted within the slide 35, and the slide 35 may move relative to the tube 90 for feeding operations of the tools 34 and 34a, in the present case trimming tools for the inner or open end of the shell 39 or 39a. The tool carrier 70 or 71 is mounted in the end of the slide 35, in the present instance it being threaded into the slide, as indicated at 96. The knockout tube 90 is of reduced diameter for the greater portion of its length, as indicated at 90a, and the tool holder 70 (or 71) is guided on this reduced portion. This forms a shoulder 97 on the tube spaced from and opposed to the inner end of the holder 70 or 71. A spring 98 embraces this reduced portion and abuts at its opposite ends against the shoulder 97 and the holder 70 or 71, thus tending to shift the tube 90 to the left as viewed in Figs. 4, 5 and 6, and normally holds its inner end against an adjustable stop 99 mounted on the housing 33 by means of a cap 100. Rather than have the end of the tube 90 directly engage the stop, it is preferred to mount a stop plug 101 in the end of the tube to engage the stop. This plug also forms a bearing for a stop rod 102 running throughout the length of the tube 90. The reduced portion 90a of tube 90 is also supported in the tool holder 70 or 71.

The reduced portion 90a of the knockout tube 90 extends into the work spindle 20 and within the collet or chuck 37 at its inner end, and carries a bearing retainer 103 (Fig. 5) having a shank 104 telescoping in the tube. Carried by this member 103 is a work locator 105 mounted to rotate in the member 103 in an anti-friction bearing 106. This work locator is retained in the member 103 by a key pin 107 extending at its inner end into an annular groove 108 in the shank

of the locator. This locator is also locked to the stop rod 102 by a transverse lock pin 109 having a keyhole shaped opening 110 to permit passage of the head 111 and lock the applicator to the rod 102 by the reduced neck portion 112. This neck portion, however, is longer than the thickness of the central portion of the pin 109 so as to permit a certain amount of relative movement between the locator and the rod. The free end of the locator 105 is adapted to seat against the inner surface of the end wall of the work piece 39, as indicated in Fig. 5, to limit the inward movement of the work piece into the chuck and properly locate it in the desired position therein, and it also acts as an ejector or knockout means for shifting the finished work piece forwardly in the chuck to a position where it may be readily grasped and removed from the chuck. A spring 113 embraces the rod 102 and by reaction on the sleeve 114 keyed to the member 90a and the inner end of shank 104 tends to move the member 103 and the locator 105 outwardly, this movement being limited by the split collar 265 (Fig. 6) in an annular groove in the rod engaging a shoulder 266 and to thus always accurately locate the locator in a given position. The locator 105 and rod 102 have limited inward movement as determined by shoulder 103a on member 103 engaging the end of the tube 90a. The pin 109 is held in the member 105 by a snap ring 115, and the pin 107 is held in position by a similar ring 116.

Tools operating on the outer end of the work piece

As a number of different operations are performed on the outer head of the work piece, in the present case a shell or casing 39 or 39a, there are a plurality of tool carriers and operating mechanisms associated with each work spindle, which are carried by the barrel 36 mounted on the shaft 2 so as to rotate with this shaft and the turret. As indicated in Fig. 8 the present machine is tooled to turn a groove in the outer surface of the shell to form the flange 117 and the groove 118 immediately back of it, to face off the end of the shell, to form a groove 119 in the end face, and to drill, ream, counterbore and countersink a central opening in the end of the shell, as indicated by the drill 120 in Fig. 8b and the reaming, counterboring and countersinking tool 121 in Fig. 8c.

The tools for turning and finishing the outer surfaces 117, 118 and facing the end of the shell are carried by a tool holder 122 (Figs. 7 and 11) mounted on a tool bar 123. This bar is mounted to rock in the barrel 36 and has a reduced extension 124 (Figs. 5 and 7) at its inner end mounted in a bearing 125 in the turret 19. The bar 123 is mounted in a tube or sleeve 126 mounted in suitable bearings 127 and 128 in the barrel 36. Bearing bushings 129 are provided for supporting the bar 123 in the tube 126 to permit turning movements of the bar within the tube. Similar bearing bushings are provided for the tube 126 in the bearings 127 and 128 to permit this tube 126 to turn in these bearings and thus turn relative to the barrel. The tool holder 122 is keyed to the bar 123 so that by rocking this bar the various tools carried by this holder are shifted to and from the work piece and are properly fed during the cutting operations. The various tools carried by this holder are indicated somewhat diagrammatically in Fig. 11, and their various positions throughout the cycle of work operations for each work piece and throughout one revolution of the turret are also indicated in this figure. These

comprise a roughing tool 130 to rough turn the groove 118 and the outer surface of the flange 117, a finishing tool 131 for finish turning these surfaces, and a facing tool 132 for rough facing and finishing the end surface of the work piece. Associated with finish tool 131 is a stop 133 to engage the inner end of this tool to limit inward movement of the tool in the holder and properly locate it after grinding. It will of course be understood that these particular tools are provided in the present showing merely to perform the operations required for the particular work piece shown, but that different tools may be provided for different operations on different work pieces.

At the other end of the tool bar 123 is mounted a lever 134 (Figs. 7, 12 and 13), this lever being keyed or otherwise secured to the bar, as this lever is a means for rocking the bar to shift the tools carried by the holder 122 to and from the work and to feed them during their cutting operations. As shown in Fig. 12 each lever carries a pair of rollers 135, 136 running on inner and outer cams 137 and 138, which impart to the lever, and therefore tool holder 122 and the tools carried thereby, their required movements throughout the cycle of operation of one complete revolution of the turret, these cams 137 and 138 being stationary and mounted in the right hand end housing 6. The direction of rotation of the lever is indicated by the arrow 139 (Fig. 12). The cycle of operations performed by these levers and the tools controlled thereby is indicated by the second from the outer circle in Fig. 22 and marked 140. This circle also shows the relative timing of these operations with respect to the other operations of the machine and the other tools.

In the movement of this lever with the turret, the work piece and the tools from just before the position *a* (Fig. 12) to somewhat beyond position *b*, the rollers 135 and 136 run on concentric portions 141 and 142 of the cams 137 and 138 respectively. During this movement the tools carried by the holder 122 are held in the neutral or intermediate position, as this is the portion of the cycle during which the chuck is open and the unloading of the finished piece from and the loading of the unfinished piece in the chuck in the work spindle are performed. This corresponds approximately to the outer arc 143 (Fig. 22) which indicates the portion of the cycle in which the work spindles are not driven and therefore are not rotating. The tools carried by the holder 122 are held in this neutral position so that they will not interfere with the loading and unloading of the work pieces. As the lever is carried forward and the roller 135 runs up on the portion 144 of cam 137 it is rocked to the right or clockwise, rocking the tool holder 122 in the same direction to carry the roughing tool 130 with a quick advance to turning position. As the roller 135 runs on the eccentric portion 145 of the cam the lever rocks slowly to feed the roughing tool 130 forward at the proper speed for the cutting operation. This is the position *c*. At the end of the rough turning operation the roller 135 runs onto the portion 146 of the cam permitting the lever to rock in the opposite direction under action of surface 138a of the outer cam on roller 136 for a quick return of the roughing tool and a quick advance of the facing tool 132 to the work, as this latter tool is located on the opposite side of the work piece from the tool 130. The roller 135 now follows along the eccentric portion 147 of the cam as shown by position 75

d while roller 136 runs on the eccentric portion 148 of the outer cam to feed the facing tool inwardly over the end face of the work piece at the proper speed to give a rough facing nut. At the end of this movement the finishing tool 131 is brought to engagement with the work piece to perform the finish turning of the surfaces 117 and 118. Then as the roller 135 runs on the portion 149 of the cam, as shown by position *e*, it is swung in the opposite direction, moving the facing tool outwardly to give the facing finish cut and shifting the tools to the neutral position as the roller runs onto the concentric portion 141. The surface of the outer cam 138 is correspondingly shaped for the roller 136 to permit these movements and supplement the action of the cam 137 to swing the lever counterclockwise and to insure that the roller 135 follows the contour of the cam 137. It will be understood that as the turret rotates and with it the barrel 36 carrying the tools, the tools associated with each work spindle move around and the rollers on the levers 134 for these five sets of tools follow around the cams 137 and 138, as indicated in Fig. 12. This figure really shows the five levers in their various positions for one position of the turret, but of course it also shows the various positions and the sequence thereof as each individual lever moves with the turret throughout a single revolution of the turret, so that the tools controlled by this lever perform one sequence of operations for each revolution of the turret.

Collet or chuck release

Associated with this control and operating means for the tool holder 122 is means for opening or releasing the chuck or collet jaws to release the finished work piece and to permit these jaws to close on an unfinished work piece during the proper portion of the revolution of the turret for the unloading and loading operations, and also in certain timed relation with the other operations of the machine. For this purpose the collet or chuck release rod 63 (Figs. 4, 5 and 7) which engages at its inner end the chuck release lever 61 (Figs. 4, 5, 7 and 17) passes longitudinally through the bar 123 and it is engaged at its opposite end by an adjustable stop 150 carried by a lever 151 mounted on each of levers 134 (Figs. 7, 12 and 13). This lever is pivoted to the lever 134 at 152 and carries a roller 153 running at the proper time onto a cam 154 to control the release and grip of the collets or chucks as each one approaches and passes through the loading and unloading positions indicated by the outer arc 143 of the work diagram of Fig. 22. Operation of the collet and chuck jaws is indicated by the inner circle 237 of Fig. 22. As each work spindle approaches its unloading position the roller 153 runs up onto the cam 154 causing its stop 150 engaging the end of the rod 63 to shift this rod inwardly or to the left to cause its opposite end to swing the lower end of the lever 61 to the left, and by shifting the ring 55 and the sleeve 42 to the left to release the collet or clutch jaws 38 and thus release the finished work piece. As the roller 153 runs off the cam 154 it swings in the opposite direction under action of the spring 155, permitting the rod 63 and lever 61 to move in the opposite direction, thus permitting the sleeve 42 to be shifted to the right under action of the springs 49 (Figs. 4 and 5) to thus clamp the jaws 38 on a new or unfinished work piece which has in the mean-

time been inserted in the chuck. A development of the cam 154 is shown in Fig. 21.

Drilling, boring and similar operations

A plurality of other operations may be performed on the outer end of the work piece during a revolution of the turret. In the present case means are provided for drilling a central opening in the end of the work piece 39 or 39a, in the present case a shell or casing, and also this drilled opening may then be reamed, counterbored and countersunk to prepare it for receiving the primer. If desired an annular groove, as indicated at 119 Fig. 8, may also be turned in the end wall. These operations are performed in certain timed relation with the operations of the roughing, finishing and facing tools carried by the carrier 122, the relative timing being indicated in the work diagram of Fig. 22. These tools associated with each work spindle are mounted on a carrier 156 (Figs. 1, 2, 7, 14 and 15) which is mounted to be swung back and forth to bring different tools into alignment with the work piece to permit the various operations thereon. Two sets of tools are carried by this carrier. In the present case there is a bar 157 (Figs. 7 and 15) mounted for sliding movement in suitable bearings in the carrier 156 and having at the end toward the turret a chuck 158 for carrying a drill 159. A similar bar 160 (Fig. 15) is similarly mounted in the carrier 156 spaced laterally to one side of the first bar and carrying at its end toward the turret suitable chucks for other tools, in this case a chuck 161 carrying a combination tool 162 providing a reamer 163 (Fig. 8), a counterbore 164, and a countersink 165. This chuck may also carry a grooving tool 166 if desired. It will be understood that one set only of these tools can operate on the work piece at one time, and therefore as indicated the carrier 156 is mounted so that it may be swung back and forth to bring the tool bars 157 and 160 alternately into alignment with the work piece in the spindle to permit the tools carried by these bars to perform the desired operations. For this purpose the carrier 156 is provided with a pair of inwardly extending arms 167 embracing the tube or sleeve 126, which as previously described is mounted for turning movement in suitable bearings 127 and 128 in the barrel 36. The arms 167 may be secured to this sleeve 126 by any suitable means as for example by providing split arms, as indicated at 168 (Fig. 15) with clamping screws 169 to clamp them about the sleeve.

The means for turning the sleeve 126 to swing the carrier 156 back and forth between its different positions comprises a lever 170 (Figs. 7 and 16) keyed to the outer end of the sleeve 126. This lever carries a pair of rollers 171 and 172 running on the inner cam 173 and outer cam 174 respectively (Fig. 16). The direction of rotation of the barrel carrying these levers, the carrier 156 and the tools carried thereby, is indicated by the arrows 175 in Figs. 14, 15 and 16. The sequences of the swinging movements of the lever 170 and the carrier 156 and their relation to the other operations of the machine are indicated by the circle 176 (Fig. 22). Five positions of the cycle comprising one revolution of the turret and the tools are indicated in Figs. 15 and 16, the positions of these two figures corresponding. It will be understood that these figures show all five carriers and all five operating levers in the positions they occupy at the points in the revolution at which they are shown, and it will also be

understood that each carrier and lever occupies each of these positions during a single work cycle, or, that is, a single revolution of the turret with its work-carrying spindles and the associated tools.

The position *f* in Figs. 15 and 16 shows the position of the carrier 156 shortly after the time the spindle carrying the finished work piece enters the unloading and loading portion of its travel, indicated by arc 143 of Fig. 22, and which is timed when the driving belts 24 are not in engagement with the spindle pulleys 23 so that the spindle is not rotating while it is moving through this part of its travel. This is also the time at which the collet or chuck is opened or released to release the work to permit removal of the finished work piece and the insertion of a new or unfinished work piece. The position *f* is about the time the chuck has been released.

The position *g* of Figs. 15 and 16 is the position toward the end of the neutral position or just before the chuck closes on an unfinished work piece, as will be seen from the inner circle 237 of Fig. 22. It will be seen from Fig. 15 that in the positions of *f* and *g* and on its movement from *f* to *g*, the carrier 156 is swung forwardly out of alignment with the work piece 39 so as not to interfere with removal of the finished work piece from the chuck or insertion of the new or unfinished work piece in the chuck. During this movement the rollers 171 and 172 (Fig. 16) run on the concentric portions 177 and 178 of the inner and outer cams 173 and 174 respectively. As the carrier moves beyond the position *g*, roller 171 runs onto the portion 179 of the cam 173, while roller 172 runs onto portion 180 of the cam 174, swinging the lever inwardly or counterclockwise to the position *h*, and swinging the carrier 156 to bring the bar 157 carrying the drill into axial alignment with the work piece, in which position it is automatically locked by a device presently to be described. It is held in this position during the drilling operation by the locking means and also the rollers 171 and 172 running on the concentric portions 181 and 182 respectively of the cams.

At the end of the drilling operation and after the drilling tool has been withdrawn, as will presently be described, the lever 170 is unlocked and the roller 171 runs onto portion 183 of the inner cam, and the roller 172 runs onto inclined portion 184 of the outer cam. This swings the lever 170 still further counterclockwise from the position *i* to the position *j*, and at the same time swinging the carrier 156 from the position *i* of Fig. 15 to the position *j*. This movement of the carrier shifts the tool bar 160 carrying the reamer, the counterbore and countersink into axial alignment with the work piece 39, and the carrier is again locked in this position while the bar 160 is advanced to carry the reamer to the reaming position and at the end of this operation to retract it by mechanism which will presently be described. During these operations the rollers 171 and 172 run on the concentric portions 185 and 186 of the inner and outer cams respectively. After the reaming tool has been withdrawn the carrier is unlocked as the roller 171 runs onto the portion 187 of the inner cam in its movement from position *j* to position *f*. This portion of the cam swings the lever 170 outwardly or clockwise again swinging the carrier 156 forwardly to the position *f* (Fig. 15) out of alignment with the work piece so that everything is cleared to permit removal of the finished work piece from the chuck.

and the insertion of a new unfinished work piece therein, as described above. To limit inward movement of the lever 170 it is provided with a lug 189 carrying an adjustable stop screw 188 which may engage the housing, as indicated in the position *j*.

The mechanism for shifting the tools carried by the carrier 156 toward and from the work and feed these tools during their working operations is shown in Figs. 7 and 14. The timing of the bar 157 carrying the drill with its relation to the other operations is shown by the circle 190 (Fig. 22) while similar timed operations for the bar 160 and the tools carried thereby and their relations to the other operations is shown by the circle 191 (Fig. 22).

The bar 157 is provided on its outer end with a head 192 (Figs. 7 and 14) provided on its upper side with a transverse groove 193 and on its under side with a similar transverse groove 194. The reamer bar 160 is provided with a similar head 195 having similar grooves 196 and 197 in its top and under sides respectively. These heads are extended inwardly to provide lugs 198 and 199 respectively, each carrying a guide pin 200 extending into openings 201 in the carrier 156, these guide pins preventing turning of the bars 157 and 160 from working reactions of the tools carried by them, the pins sliding in these openings as the bars are shifted longitudinally.

Each of these tool bars 157 and 160 is shifted by a lever 202 (Figs. 7 and 14) longitudinally forward and back in their carrier 156 in proper timed relation with the other operations, and when their carrier 156 is in the proper positions. This lever 202 is substantially U-shaped, as shown in Fig. 14, and is pivoted at the free ends of its side arms on a transverse shaft 203 mounted in the barrel 36. This lever carries on its outer transverse portion a roller 204 running in a cam 205, a development of which is shown in Fig. 20, this cam being stationary and mounted in the right end housing 6. Only one side of this cam is shown in Fig. 14. The lever 202 carries a finger 206 (Figs. 7 and 14) which is adapted on certain positions of the heads 192 and 195 of the tool bars to enter the grooves 193 and 196 to connect the bars with the lever 202, as will presently be more fully described. Means are also provided to lock each of the tool bars 157 and 160 in retracted position while the other tool bar is being operated by the lever 202 to shift the tool or tools carried by the respective bar. This locking means comprises a stop 207 mounted in the barrel 36, there being one of these stops for each pair of bars 157 and 160, as is shown in Fig. 14. Each stop has two outwardly extending spaced lugs 208 and 209 adapted to enter the grooves 194 and 197 in the under side of the heads 192 and 195 respectively, when the carrier 156 is swung to its opposite extreme positions, as indicated in Fig. 14, and thus lock the particular head and its tool bar against longitudinal movement while the carrier 156 is in this position. The lug 209 is somewhat longer than the lug 208 so that when the carrier 156 is in the neutral position from *j* to *g* of Fig. 15, both bars 157 and 160 are locked in the retracted position.

Associated with each lever 170 is a locking plunger 210 (Fig. 7), mounted in the barrel 36 in suitable bearings 211 and having a tapered end 212 adapted to enter a similarly tapered opening or recess 213 in each of two bushings 214 and 215 mounted in each lever 170. These bushings are spaced laterally at the proper dis-

tance, as shown in Fig. 16, so that one or the other is in alignment with locking plunger 210 when either one of the tool bars 157 or 160 carried by the carrier 156 is in alignment with a work spindle, so that the tapered end of the plunger may at this time enter the tapered opening in the bushing to accurately center and line up the tool bars and tools with the work and lock the carrier and the tool bar in this position. 5 A spring 216 tends to shift this plunger to the locking position and it is retracted at the proper time to release the carrier by the lug 217 on one arm of the lever 202 entering a notch 218 in one side of the plunger and reacting against the left hand end of this notch, as shown in Fig. 7, to retract the plunger from the locking position when the lever 202 is swung to the right to its extreme outer position, as shown in Fig. 7, and will hold the locking plunger in the released position as long as this lever 202 is in the extreme retracted position. While the plunger is in this position the lever 170 for shifting the tool carrier 156 is unlocked and therefore the tool carrier is unlocked so that it may be swung to different positions by the cams 173 and 174.

As indicated, the tool bars 157 and 160 and the tools carried thereby are shifted in certain timed relation with the other operations and at the proper positions in the revolution of the 10 turret and the barrel 36 by the cam 205, a development of which is shown in Fig. 20. These operations and the movements and positions thereof are shown by the circles 190 and 191 (Fig. 22), 190 showing the operation of bar 157 and the tool (drill) carried by it, and 191 showing the operation of bar 160 and the tools carried thereby. In the movement from position *j* to position *g* (Figs. 14, 15 and 16) the roller 204 runs on the straight forward edge (the lower edge of Fig. 20) of the portion 219 of this cam, 20 so that the lever is fully retracted and the tools carried by the bars 157 and 160 are fully retracted to maintain the tools retracted at their full distance from the work piece. At the same time, 25 as above described, the carrier 156 is swung fully to the right as shown in Fig. 15, by the cams 173 and 174 and held thereby by the concentric portions 177 and 178 of the cams to maintain the tools out of alignment with the work piece. This 30 leaves the space in front of the work spindle in this position free for removal of the finished work piece from the chuck and insertion of a new unfinished piece in the chuck. As previously described, these swinging movements of the carrier 156 with relation to the movements of tool bars 157 and 160 are shown by the circle 176 of Fig. 22.

After an unfinished work piece has been inserted in the spindle chuck and it passes beyond 35 position *g* (Figs. 14, 15 and 16) the carrier 156 is swung back by its cams 173 and 174 to bring the tool bar 157 carrying the drill into alignment with the work piece, as indicated in Fig. 15. At this time, as shown in position *h* (Fig. 14), the head 192 on this bar 157 is in the notch between the locking lugs 208 and 209 and is therefore unlocked. The head 195 on the reamer bar 160, 40 however, is still in alignment with the lug 209 which is in the slot 197 in the underside of this head, so that the bar 160 is locked against longitudinal movement. However, as the head 192 on the drill bar 157 is in the central position between the two locking lugs, it is in alignment with the finger 206 carried by the lever 202 so 45 that this finger 206 is now seated in the groove

193 (Figs. 7 and 14) in the top of the head 192, as shown at position *h* in Fig. 14. Then as the roller 204 on the lever 202 enters the incline 220 (Fig. 20) of the cam 205, this lever is swung to the left as shown in Fig. 7, and as the tool bar 157 is now connected to this lever through the head 192 and the finger 206, this tool bar and the tool, in the present case the drill, carried thereby, is advanced by rapid movement toward the work piece and into position for the drilling operation. The roller 204 now enters the slightly inclined portion 221 of the cam 205 which feeds the drill forwardly at the proper speed for the drilling operation. After the drilling is completed roller 204 enters the forwardly inclined portion 222 of the cam, giving a rapid retraction of the bar 157 and the drill from the drilling position and the lever 202 and the bar are carried to their extreme retracted position. At this time the roller is in the straight portion 223 of the cam and no movement is imparted to the lever 202. At this time portion 184 of cam 174 (Fig. 16) swings the lever 170 and with it the carrier 156 to the left to carry the tool bar 157 out of alignment with the work piece. This carries the head 192 away from the finger 206 and shifts it into alignment with the locking lug 208, as shown in position *j* (Fig. 14). This releases the head 192 from its connection to the lever 202, but carries the groove 194 in the under side of this head onto the lug 208 so that the head 192 and the bar 157 are now locked against longitudinal movement.

This swinging movement of the carrier 156, however, has carried the head 195 on the tool bar 160 carrying the reamer and similar tools into alignment with the work piece and brought this head 195 into the intermediate position between the two locking lugs 208 and 209 as shown at *j* (Fig. 14) so that it is unlocked. This head 195 is now in alignment with finger 206, and this finger is therefore seated in the groove 196 in the top of the head 195 and this head and the bar 160 are therefore connected with the lever 202. The roller 204 on this lever now enters the inclined portion 224 of the cam 205, shifting the bar 160 and the tools carried thereby (in this case the reamer and associated tools) rapidly toward the work piece to the working position. The roller 204 now enters the less steeply inclined portion 225 of the cam which feeds the reaming tool forwardly at the proper speed for the reaming operation. The roller 204 at the end of this reaming operation enters the still less inclined portion 226 of the cam, giving a proper movement for the counterboring operation, and as it passes through the nearly straight portion 227 the countersinking operation is performed. The roller then enters the inclined portion 228 which swings the lever 202 to its extreme retracted position, carrying with it the tool bar 160 to give rapid retraction of the reamer and similar tools from the work piece. The roller 204 now runs onto the straight front edge of the portion 219 of the cam 205 which holds it in the retracted position for the unloading of the finished work piece and loading of an unfinished work piece and until the beginning of the next cycle. Shortly after retraction of the lever 202 and the bar 160 the carrier 156 is swung by its cams 173 and 174 to the position shown at *f* in Figs. 14, 15 and 16. This shifts the tools carried by this carrier out of alignment with the work piece and carries both heads 192 and 195 into alignment with the lock lug 209, so that this lug now seats in the grooves 194 and 197 in the under sides of

these tool heads respectively, as shown in Fig. 14, so that as long as the carrier 156 is in this position both tool bars 157 and 160 are locked in their fully retracted positions.

5 *Work trimming and knockout operations*

During the rotation of the turret and consequent movement of the work piece from the position *g* (Fig. 15) clockwise around to the position *f*, work operations may also be performed on the other or inner end of the work piece. In the present showing the inner end of the shell 39 or 39a is trimmed to give the proper length to the shell and a straight even edge. This operation is performed by the tool 34 or 34a, as previously described. The movements of this tool and its relation to the other operations are shown by the circle 84a of Fig. 22, and the movements are imparted to this tool by the cam 84 (Figs. 4, 6, and 10) a development of which is shown in Fig. 18. This cam operates the roller 83 on the block or carrier 74, which block, as previously described, is connected to the slide 35 by means of the adjustable screw 81.

25 As shown in Figs. 4, 5, 6, 9 and 10, the work spindle and the slide 35 in alignment therewith are at the top of the vertical center line of the machine, and therefore this roller 83 is substantially on the center line, indicated at the extreme right of Fig. 18. As the turret moves forwardly to carry the work spindle from this position, the collet or clutch closes to grip the work, and the roller 83 enters the inclined portion 229 of the cam 84, shifting the slide 35 and the trimming tool 34 or 34a carried thereby rapidly toward the inner end of the work piece. The roller then runs on the slightly inclined portion 230 of the cam which feeds the trimming tool forwardly at the proper speed for the trimming operation. The roller then runs into the inclined portion 231 of the cam, giving a quick retraction of the slide 35 and the trimming tool to the extreme retracted position. The roller 83 now runs in the straight portion 232 of the cam and retains the trimming tool in this retracted position while the other operations are being performed by the other various tools on the work piece.

35 The trimming tool is held in this position, as shown by the outer circle 84a of the diagram, Fig. 22, until the other work operations are completed and the spindle is brought into the unloading position, which is substantially the position *f* of Fig. 15. As it moves to this position the collet or clutch is released by the rod 63 and lever 61 operated by the lever 151 through the cam 154 (Figs. 5, 7, 12, 13, 17 and 21). At about this time the roller 83 approaches the right hand end of the straight portion 232 of cam 84 (Fig. 18) and the roller 85 (Fig. 10) on the carrier block 74 drops into the recess 86 in the cam 84. 40 This permits the opposite end of the latch lever 75 to enter the annular groove 89 (Figs. 4, 6 and 9) in the work ejector or knockout tube 90, thus connecting the block or carrier 74 to this tube 90. The roller 83 now runs into the inclined portion 233 of the cam, giving the tube 90 a rapid movement forwardly, carrying with it the locator 105 engaging the inner side of the outer end of the work piece, and as the collet or chuck has been released it shifts the finished work piece a certain amount out of the chuck, depending on the stroke imparted to the tube 90. This is sufficient to expose enough of the outer end portion of the finished work piece to provide a ready grip by the operator for removing the work piece 45 from the chuck and the work spindle. In the

present case it is given a movement of nearly two and one-half inches to thus expose a corresponding amount of the finished work piece. After a short dwell in the straight portion 234 of the cam, roller 83 passes into the inclined portion 235, which gives a rapid withdrawal of the locator 105 to its original position, after which the roller 83 enters the straight portion 236 of the cam and the roller 85 on the latch lever rides out of the depression 86 in the outer surface of the cam onto the outer periphery of the cam, withdrawing the inner end of the latch 75 from the groove 89 in the ejector or knockout tube 90. The block or carrier 74 is now disconnected from the tube 90 and the block may be shifted forwardly by the inclined portion 229 of the cam to the trimming position, as previously described, independently of the tube 90 and without shifting this tube. Thus for the trimming operation the block or carrier 74 is disconnected from the tube 90 and moves independently thereof. During the knockout operation while the roller 83 is running in the inclined portion 233, the roller 85 on the latch lever is in the depression 86 in the outer surface of the cam. This depression is therefore made sufficiently wide, as indicated in Fig. 18, to permit this movement.

Work locating means

As indicated by the arc 143 of the chart (Fig. 22), while a work spindle is moving from a position substantially corresponding to or a little before the position *f* of Fig. 15, to and somewhat beyond the position *g*, the spindle pulley 23 (Figs. 4 and 11) is out of contact with the driving belts 24 (Fig. 11) as the belt is lifted away from the pulley by the idler 27. Therefore there is no drive for the work spindle during this movement, and immediately after the pulley leaves the belt the collet or chuck release rod 63 (Figs. 4, 5, 7 and 17) operates to swing lever 61 and with it the collet control sleeve 42 to the left to release the chuck. In this movement the collar 57 (Figs. 4 and 5) presses against the shoulder 58 on the ring 55 and this friction quickly stops rotation of the work spindle. The roller 153 (Figs. 12 and 13) of the collet release lever is running on the high part of the cam 54 and throughout the movement from just prior to position *f* to somewhat beyond position *g* retains the clutch in the open position, as indicated by the inner circle 237 (Fig. 22) to permit removal of the finished work piece and insertion of a new unfinished work piece, as previously described. It will be understood that the operator performs these loading and unloading operations while the turret and the associated tools continue to rotate, and the various working operations are all performed on the work piece while the turret continues to rotate, so that there is no stopping of the turret to hold the work at different working stations and no indexing mechanism or indexing operation for the turret is required.

Means is provided to insure that the work piece (in this case the shell 39 or 39a) is fully inserted in the work holding chuck. This device is shown in Figs. 23 and 24. Mounted on the base or frame 1 is a rear bracket 238 (Figs. 1 and 2) and mounted on this bracket and the other side of the frame and extending over the top of the turret is a cross bracket 239 to which the forward end of the motor supporting bracket 28 is secured. Mounted on the forward side of this bracket is a plate 75 out tube 90 is keyed to this tube by a pin 264

or bracket 240 (Figs. 23 and 24) carrying an air cylinder 241. This cylinder is mounted on a support 242 pivoted to the bracket 240 at 243, and a spring 244 tends to swing it clockwise and retain it against an adjustable stop 245. Within the cylinder is a piston 246 operating a piston rod 247 carrying a head 248. Pivoted on this head at 249 is a lever 250 having an arm 251 adapted to engage the top of an arm 252 on the support 242. The depending arm of lever 250 carries a finger piece 253 adapted to engage the end of the work piece 39 or 39a. A spring 254 is connected to the lever 250 and the cylinder 241 and tends to lift the lever and the piston and also to swing the lower end of the lever and the finger 253 outwardly to the dotted line position, this outward movement being limited by the lug 255 on the lever engaging a stop 256. Inward movement of the finger piece 253 is limited by the stop 257 being engaged by the arm 251. The cylinder is connected by a flexible connection 258 with an air valve 259 mounted on the bracket 240. This valve is connected with any suitable source of supply for compressed air by pipe 260 and is controlled by a lever 261 having a roller 262 adapted to be engaged by a cam 263 mounted on the turret 19, there being one of these cams adjacent each work spindle. The cams are so located that just before the chuck jaws close after a work piece has been inserted in the chuck this cam engages the roller 262 to operate the valve to supply compressed air to the cylinder 241. This forces the piston downwardly to the full line position of Fig. 23, carrying with it the lever 250 and the finger 253, the upper position being indicated at 253a. The piston and the lever move downwardly, bringing the finger to the position 253b in front of the work piece 39, at which time the arm 251 engages the top of the arm 252 of the support. Further downward movement of the piston and the head 248 swings the lever clockwise carrying the finger 253 inwardly from the dotted position 253b to the full line position, as indicated by the arrows, carrying this finger against the end of the work piece and forcing the work piece fully into the chuck against the locator 105 (Fig. 5) and retains it there until the chuck closes. This insures that each work piece is fully inserted in the chuck and that all the work pieces are located in the same relative position in their respective chucks and work spindles and in proper relation to the tools associated with this spindle. After the chuck closes the cam moves beyond the roller 262, permitting the valve 259 to close and at the same time release the air above the piston 246, permitting the piston to rise under action of the spring 254 and move the finger 253 to its retracted position out of the way of the work piece and the tools. If a work piece or tool should project sufficiently to engage the finger piece 253 on its forward edge the support 242 will swing on its pivot 243 counterclockwise against the action of the spring 244, so that nothing will be broken, and after the projecting element has passed the finger 253 this member and the support will be swung back to normal position by the spring 244.

Automatic stop

Means is provided for automatically stopping rotation of the turret should for any reason the work piece not be fully inserted in the chuck to the proper location. This is indicated in Figs. 4, 5 and 6. As indicated in Fig. 5 the sleeve 114 within the reduced portion 90a of the work knocked on the forward side of this bracket is a plate 75 out tube 90 is keyed to this tube by a pin 264

so that this sleeve forms an abutment for the spring 113 which tends to shift the bearing retainer and the locator 105 to the right. This movement is limited by the stop rod 102, the locator 105 being keyed to it by the cross pin 109. The movement of the rod 102 to the right is limited by a split collar 265 (Fig. 6) seated in a groove adjacent the other end of the rod 102. Movement of this rod to the right is therefore limited by this collar engaging a shoulder 266 in the stop plug 104. This arrangement permits limited movement of the locator 105 and the rod 102 relative to the ejector or knockout tube 90, and both are forced inwardly by the work piece as it is forced into the chuck until their movement is stopped by shoulder 103a on the member 103 engaging the end of tube 90a (Fig. 5), the work piece being forced to this position by the mechanism shown in Figs. 23 and 24, previously described. Inward movement of tube 90a and 90 is limited by the adjustable stop 99 (Figs. 4 and 6). A spring pressed plunger 267 (Fig. 6) engages the inner end of the rod 102 and is held against the end of this rod by the spring 268 reacting at one end against the head of the plunger and at the opposite end against a shoulder 269 in the adjustable stop screw 99. Adjustably threaded into the plunger 267 is a cam screw 270 projecting beyond the screw 99, and if the work piece has not been fully inserted in the chuck and therefore this cam screw 270 is not shifted to its full left-hand position, it will engage means for operating a microswitch 280 controlling relays (not shown) for operating a control switch (not shown) for the motor 14 to stop the motor and therefore stop the rotation of the turret.

This device is shown somewhat diagrammatically in Fig. 4 and comprises a bracket 271 mounted on the housing 5. Adjustably mounted in this bracket is a sleeve 272 carrying at one end a support 273 for a pivoted lever 274. This lever carries a block 275 in position to be engaged by cam screw 270 if the work piece is inserted in the proper position in the chuck, and thus permits continuous operation of the machine. This lever is engaged by a pin 276 slideable in the sleeve 272 and having a reduced portion 277 embraced by a spring 278 tending to force it to the right against the lever 274. Movement of pin 276 and lever 274 outwardly or to the right is limited by a lug 286 on bracket 273 overhanging the lever 274. At its opposite end pin 276 projects from the sleeve to engage the operating means 279 of the micro-switch 280. As previously indicated, this micro-switch controls suitable relays for controlling operation of the motor 14. These relays and their connection to the micro-switch and the control switch for the motor are not shown as they are of well known construction and operation. Thus, if the work piece is not properly inserted in the chuck the locator 105 (Fig. 5) and the rod 102 will not be shifted properly to the left and therefore the cam screw 270 will not be shifted to its extreme outer position. As the turret and the housing 5 rotate to carry this member 270 by the block 275, under these conditions it will not engage the block and will therefore not throw the micro-switch 280 to permit continuous rotation of the turret, and this switch will then cause the relays to operate to stop the motor 14 and stop rotation of the turret. If, however, the work piece is fully inserted to its proper position the locator 105, the rod 102 and the stop cam 270 will be shifted to their extreme left position so that this member 270 will

engage the block 275, throw the switch control to permit the motor 14 to continue to operate, and thus the turret will continue to rotate.

Should a work piece be improperly located and rotation of the turret should be stopped, it will stop with the chuck or collet release lever 151 (Fig. 18) over a plunger 281 (Figs. 3, 7 and 13) slidably mounted in the block 282 mounted on the right end housing 6. At its outer end this plunger engages a hand lever 283 pivoted to the block 282 at 284 and projects to a position in front of the machine where it is easily accessible to the operator. Plunger 281 is normally shifted to the right outwardly against this lever by a spring 285 (Fig. 7). This plunger is located just beyond the collet or catch release cam 154 which is in alignment with the position the roller 153 will occupy should the turret be automatically stopped as above described if the work piece is not properly inserted or located in the chuck; that is, the turret will be stopped before the improperly located work piece is carried to a position where any of the tools would start to perform their operations on this work piece. Thus in this event the operator by manipulating the lever 283 can force the plunger 281 inwardly to swing the roller 153 and its lever 151 to the left as shown in Fig. 13 to shift the clutch release rod 63 and thus shift the sleeve 42 (Fig. 5) to open or release the chuck. This will thus release the work piece and permit the operator to either remove it from the chuck and insert a new work piece, or will permit him to force the piece into the chuck to the proper position, or he can remove the work piece and start the machine operating without a work piece in this particular spindle until it again comes back to the loading position.

It will thus be seen from the above that the turret with the work spindles and the tools associated with each spindle rotate continuously; that operations can be performed on both ends of the work piece with a single chucking operation on the work piece and while the work piece is held in the chuck in the work spindle; that all of the working operations are performed on the work piece during a single rotation of the turret, and thus are performed while the spindle carrying the work piece is moving around with the turret from the loading to the unloading position; that this portion of the path of movement of the work piece comprises a greater portion of one revolution of the turret, so that practically the whole time of one revolution is available for the operations performed on each work piece, permitting the various working operations of turning, drilling, boring, trimming, etc. to be performed at the proper speeds and at sufficiently low speeds so as to give maximum life to the tools and reduce to a minimum the wear on these tools, and thus reduce to a minimum the time required for the machine to be stopped for regrinding the tools and resetting them to compensate for wear. The finished work piece is unloaded from the chucks by the operator standing in front of the machine and a new unfinished work piece is inserted in the chuck while the chuck is open during a short portion of the rotation of the turret, as described above and as shown in the work chart, Fig. 22, the speed of course being controlled to permit time enough for the operator to safely perform these operations. At this time the pulleys 23 on the respective spindles are not in contact with their driving belts 24 and the spindles are stopped as described above in connection with the operation of

the spindles. As the work can be performed on both ends of the work piece while it is in its respective spindle it is not necessary to perform the work operations on one end of the work piece in one machine, then remove it from that machine and reverse it and run it through another machine to perform the operations on the other end of the work piece, but in this machine the operations on both ends are performed at the same time in the same machine, and at a single chucking operation.

Having thus described the nature of my invention, what I claim is:

1. In a machine of the character described, a central shaft, spaced housings carrying bearings adjacent the opposite ends of the shaft for supporting the shaft, a turret mounted on and secured to the shaft to rotate therewith, a plurality of work spindles mounted in the turret, work holding means in each spindle opening through opposite sides of the turret, a support mounted on and secured to the shaft at each side of the turret to rotate therewith, tool carriers mounted on said supports and movable toward and from work pieces mounted in the spindles, said turret and supports being mounted on the shaft between the shaft bearings so that the shaft is supported at spaced points at opposite sides of the turret and supports, and means for rotating the shaft to rotate the turret and said supports.

2. In a machine of the character described, a rotatable turret, a work carrying spindle mounted in the turret comprising a tube extending transversely of the turret and open at both ends, a collet in the spindle slit longitudinally for a portion only of its length to form spring arms carrying work gripping jaws at their outer ends, the inner unslit end of the collet forming a support for the work piece spaced from the jaws, a sleeve embracing the collet and slideable in the spindle, means for sliding the sleeve, and cooperating means on the sleeve and the jaws to clamp the jaws on a work piece.

3. In a machine of the character described, a rotatable turret, a plurality of work spindles mounted in the turret, a work holding chuck in each spindle comprising movable jaws, a sleeve mounted to slide in the spindle provided with means cooperating with the jaws to clamp them on a work piece, springs tending to shift the sleeve to clamp the jaws, a second sleeve mounted to slide on the spindle and connected with the first sleeve, said second sleeve provided with a flange, a collar embracing said latter sleeve and adapted to engage the flange to shift the sleeve to release the chuck jaws, a lever connected to the collar, means for driving the spindles, means for disconnecting the driving means from the spindles during a portion of the rotation of the turret, and means for operating the lever when the driving means is disconnected to release the jaws and to press the collar against the flange and by frictional action thereon to stop rotation of the spindle.

4. In a machine of the character described, a rotatable turret, a plurality of work spindles mounted in the turret, a work holding chuck in each spindle comprising movable jaws, a sleeve mounted to slide on the spindle and provided with a flange, means operated by the sleeve to release the chuck jaws, a collar embracing the sleeve and adapted to engage the flange to shift the sleeve, a lever connected with the collar, means for driving the spindles, means for disconnecting the

75

driving means from the spindles in succession during a portion of the turning movement of the turret, and means for operating the lever to press the collar against the flange to release the jaws and by frictional action between the collar and the flange to stop rotation of the spindle when said driving means is disconnected.

5. In a machine of the character described, a rotatable turret, a plurality of hollow work spindles mounted in the turret and open at both ends, a chuck in each spindle for gripping a work piece, tools on each side of the turret and movable with the turret for performing operations on both ends of a work piece in the chuck, a tool carrier on the inner side of the turret and movable longitudinally to shift the tool on that side of the turret to operate on the inner end of the work piece, a knockout means extending into the work piece from the inner end thereof and movable with said tool carrier, means connected with the tool carrier for shifting it, and means operated in certain timed relation with operations on the work piece to connect the tool carrier operating means with the knockout means to shift a work piece in the chuck and to disconnect said operating means from the knockout means to permit shifting of the tool carrier independently of the knockout means.

6. In a machine of the character described, a rotatable turret, a plurality of hollow work spindles mounted in the turret and open at the front of the turret for insertion and removal of a work piece in and from the spindle, each spindle being also open at its other end to permit operations on the inner end of the work piece, a tool carrier at the inner side of the turret movable toward and from the spindle, a block connected to the carrier, a knockout means associated with said carrier and engaging the work piece, means for shifting the block, and means operated in timed relation with operation of the block to connect the block with and disconnect it from the knockout means.

7. In a machine of the character described, a rotatable turret, a plurality of hollow work spindles mounted in the turret and open at the front of the turret for insertion and removal of a work piece in and from the spindle, each spindle being also open at its other end to permit operations on the inner end of the work piece, a tubular tool carrier mounted to slide toward and from the inner end of the work piece, a block connected to the carrier for operating it, a knockout member engaging the work piece and mounted in said carrier, a cam for shifting the block to shift the carrier, a catch operable to connect the block with the knockout member and disconnect it therefrom, and a cam to operate the catch in certain timed relation with shifting of the block.

8. In a machine of the character described, a rotatable turret, a plurality of work spindles in the turret open at both sides of the turret, a tubular tool slide at the rear of the turret associated with each spindle, a housing in which the tool slides are mounted and rotatable with the turret, a knockout member mounted within each slide and extending into the corresponding spindle to shift a work piece therein, a block connected to the slide, a stationary cam, means on the block running on the cam to shift the slide, a catch lever carried by the block and adapted to engage the knockout member to cause it to move with the block, and cam means controlling the connection of the lever with the knockout member.

9. In a machine of the character described, a rotatable turret, a plurality of work spindles in the turret open at both sides of the turret, a knockout member extending into each spindle from the rear side of the turret, a tubular tool slide embracing each knockout member and movable relative thereto, a housing rotatable with the turret in which the slides are mounted, a block connected to each slide, a stationary cam, means on the blocks cooperating with the cam to shift each tool slide relative to its spindle, a catch on each block adapted to engage the knockout means to cause it to move with the block, and cam means controlling said catch in timed relation with operation of the slide.

10. In a machine of the character described, a rotatable turret, a plurality of work spindles mounted in the turret and open at the front side of the turret for insertion of work pieces, a housing at the rear side of the turret rotatable with the turret, a knockout tube for each spindle mounted in the housing, a locator carried by each tube at the forward end thereof to be engaged by a work piece as it is inserted in a spindle and limit its movement into the spindle, a stop rod in the knockout tube connected to the locator, said locator and stop rod having limited movement relative to the tube, a spring tending to shift the rod and locator to their extreme forward position, means to limit their movement in the opposite direction to locate a workpiece, a driving means for rotating the turret, a control means for rendering said driving means effective or ineffective, and means shiftable with the stop rod adapted to affect the control means according to the position of the stop rod.

11. In a machine of the character described, a rotatable turret, a plurality of work spindles in the turret and open at the forward side of the turret for insertion and removal of work pieces, a locator extending into the spindle from the opposite side of the turret to locate the work piece, a stop rod connected to the locator, means for mounting the rod and locator permitting limited movement thereof, a spring tending to shift the locator forwardly, means limiting rearward movement of the locator, driving means for rotating the turret, control means for said driving means, means located by said rod adapted to cooperate with said control means by movement with the turret to determine its control of the driving means, and means at the forward side of the turret to shift a work piece into the spindle against the locator.

12. In a machine of the character described, a rotatable turret, a work spindle in the turret open at the front thereof for insertion and removal of work pieces, a work gripping chuck mounted in the spindle, means mounted in the turret for releasing the chuck, means extending forwardly from the turret for operating said chuck releasing means, and means located forwardly of the turret for operating said forwardly extending means.

13. In a machine of the character described, a rotatable turret, a plurality of work spindles mounted in the turret open at the forward side thereof for insertion and removal of work pieces, a work holding chuck in each spindle, means mounted in the turret for releasing the chucks, a rod associated with each spindle for operating the chuck releasing means and extending forwardly from the turret, a support for said rods rotating with the turret, a stationary cam, and means on said support adapted to cooperate with

the cam to shift the rods in succession as the turret rotates to release the chucks.

14. In a machine of the character described, a rotatable turret, a plurality of work spindles mounted in the turret open at the forward side thereof for insertion and removal of work pieces, a work holding chuck in each spindle, means mounted in the turret for releasing the chucks, a support mounted forwardly of the turret and rotatable therewith, a tool bar associated with each spindle and mounted for rocking movements in the support, a tool holder on each bar, a rod mounted in each bar and extending to a position to operate the chuck release for its respective spindle, stationary cam means, means cooperating with said cam means to rock the bar as the turret rotates, and means to shift the rods to release the respective chucks in succession as the turret rotates and in timed relation with the operation of the tool bars.

15. In a machine of the character described, a rotatable turret, a work spindle in the turret open at the front thereof for insertion and removal of work pieces, a work gripping chuck mounted in the spindle, means mounted in the turret for releasing the chuck, a support mounted forwardly of the turret to rotate therewith, a tool bar mounted for rocking movements in said support, a chuck release rod mounted in the bar and connected with the chuck release means in the turret for operating it, a lever mounted on the bar for rocking it as the turret rotates, a lever mounted on the first lever for operating the chuck release rod, and means for operating said levers in timed relation with operation of the turret.

16. In a machine of the character described, a rotatable turret, a work spindle in the turret open at the front thereof for insertion and removal of work pieces, a work gripping chuck mounted in the spindle, means mounted in the turret for releasing the chuck, a support mounted forwardly of the turret, for movement therewith, a tool bar mounted for rocking movements in the support, a chuck release rod mounted in the bar and extending to a position to operate the chuck release means, a lever mounted on the bar, a stationary cam cooperating with said lever through rotative movement of the support to rock the bar, a lever mounted on the first lever for operating the chuck release rod, and a stationary cam for operating said latter lever in certain timed relation with operation of the bar and turret.

17. In a machine of the character described, a rotatable turret, a work spindle in the turret open at the front thereof for insertion and removal of work pieces, a work gripping chuck mounted in the spindle, means mounted in the turret for releasing the chuck, a support mounted forwardly of the turret to rotate therewith, a chuck release rod mounted in the support and extending to a position to operate the chuck release means, a stationary cam for operating the rod through movement of the support to release the chuck, and a hand operated means located forwardly of the cam adapted to operate said rod to release the chuck after the chuck has closed including means accessible to the operator at the outside of the machine for operating it.

18. In a machine of the character described, a rotatable turret, a plurality of work spindles mounted in the turret and open at the front thereof for insertion and removal of work pieces, a work holding chuck in each spindle, a release

means for each chuck mounted in the turret, a support mounted at the forward side of the turret to rotate therewith, a tool bar for each spindle mounted for rocking movement in the turret, a chuck release rod in each bar extending to a position to operate the chuck release for its respective spindle, a lever on each tool bar, stationary inner and outer cams, spaced rollers on each lever running on the respective cams as the turret rotates to operate the lever and the bar, a lever mounted on each of the first levers to operate the chuck release rod, and a stationary cam to be engaged by the second levers at a given part of their movement with the turret to release the respective chuck.

19. In a machine of the character described, a rotatable turret, a work spindle in the turret, a support mounted forwardly of the turret to rotate therewith, a carrier mounted on the support for lateral movements, a pair of laterally spaced tool carriers mounted on the first carrier for movements toward and from a work piece in the spindle, means operated in certain timed relation with rotation of the turret to shift the first carrier to bring the tool carriers in succession into alignment with the spindle during a revolution of the turret, and means to shift the respective tool carriers while so positioned to and from operative position with respect to the work piece.

20. In a machine of the character described, a rotatable turret, a work spindle in the turret, a support mounted forwardly of the turret to rotate therewith, a carrier mounted on the support for lateral movements, a pair of laterally spaced tool carriers mounted on the first carrier for movements toward and from a work piece in the spindle, means for locking the respective tool carriers in their retracted positions made effective and ineffective by lateral movements of the first carrier, means operated in certain timed relation with rotation of the turret to shift the first carrier to unlock the respective tool carriers and bring them successively into operative position with respect to the spindle during a revolution of the turret, and means for operating the respective tool carriers while so positioned to permit operations on the work piece.

21. In a machine of the character described, a rotatable turret, a work spindle in the turret, a support mounted forwardly of the turret to rotate therewith, a carrier mounted on the support for lateral movements, a plurality of laterally spaced tool carriers mounted in the first carrier and movable relative thereto to permit operations of tools carried thereby on a work piece in the spindle, means operated in certain timed relation with rotation of the turret to shift the first carrier to bring the tool carriers successively into operative position with respect to the spindle during a revolution of the turret, and means for operating the respective tool carriers while so positioned to permit operations on the work piece.

22. In a machine of the character described, a rotatable turret, a work spindle in the turret, a support mounted forwardly of the turret to rotate therewith, a carrier mounted on the support for lateral movements, a plurality of laterally spaced tool carriers mounted in the first carrier and movable relative thereto to permit operations of tools carried thereby on a work piece in the spindle, means for locking the respective tool carriers in their inoperative positions made effective and ineffective by lateral movements of the first carrier, means operated in certain timed

relation with rotation of the turret to shift the first carrier to unlock the respective tool carriers and bring them successively into operative position with respect to the spindle during a revolution of the turret, and means for operating the respective tool carriers while so positioned to permit operations on the work piece.

23. In a machine of the character described, a rotatable turret, a work spindle in the turret, a support mounted forwardly of the turret to rotate therewith, a carrier pivotally mounted on the support for lateral swinging movements, a pair of laterally spaced tool carriers slidably mounted in the first carrier for movement toward and from the spindle, means connected with the first carrier to swing it in certain timed relation with rotation of the turret to bring the tool carriers in succession into alignment with the spindle during a revolution of the turret, means mounted on the support for operating the tool carriers, cooperating means on said operating means and each tool carrier to connect this carrier with the operating means only when the carrier is in alignment with the spindle, and means for operating the operating means in timed relation with swinging movements of the first carrier to shift the respective tool carriers toward and from the spindle.

24. In a machine of the character described, a rotatable turret, a work spindle in the turret, a support mounted forwardly of the turret to rotate therewith, a carrier mounted on the support for lateral movements, a pair of laterally spaced tool carriers mounted on the first carrier for movements toward and from a work piece in the spindle, laterally spaced locking lugs mounted on the support, cooperating means on each tool carrier to engage one of said lugs to lock the respective carrier in retracted position when out of alignment with the work spindle and free from said lugs when in alignment with the spindle, means operated in certain timed relation with rotation of the turret to shift the first carrier to bring the tool carriers in succession into alignment with the spindle during a revolution of the turret, operating means on the support for operating the tool carriers, and cooperating means on each tool carrier and said operating means arranged to connect each tool carrier with said operating means only when the tool carrier is unlocked and in alignment with the spindle.

25. In a machine of the character described, a rotatable turret, a work spindle in the turret, a support mounted forwardly of the turret to rotate therewith, a carrier pivotally mounted on the support for lateral swinging movements, a pair of laterally spaced tool carriers slidably mounted in the first carrier for movement toward and from the spindle, means for swinging the first carrier in certain timed relation with rotation of the turret to bring the tool carriers in succession into alignment with the spindle during a revolution of the turret, means for locking the respective tool carriers in their retracted positions when out of alignment with the work spindle and made effective and ineffective by lateral movements of the first carrier, a lever pivoted on the carrier, cooperating means on the lever and each tool carrier to connect this carrier with the lever only when the carrier is in alignment with the work spindle and released from the locking means, and means for operating the lever to shift the tool carrier connected therewith toward and from the spindle.

26. In a machine of the character described, a

rotatable turret, a work spindle in the turret, a support mounted forwardly of the turret to rotate therewith, a carrier pivotally mounted on the support for lateral swinging movements, a pair of laterally spaced tool carriers slidably mounted in the first carrier for movement toward and from the spindle, a pair of laterally spaced locking lugs mounted on the support, a head on each tool carrier having a groove arranged to receive one of said lugs as the first carrier is swung to shift the tool carriers out of alignment with the spindle to lock the tool carrier in its retracted position and free from the lugs when the tool carrier is in alignment with the spindle, means to swing the first carrier in timed relation with rotation of the turret to bring the tool carriers in succession into alignment with the spindle during a revolution of the turret, a lever pivoted to the support, a finger mounted on the lever, the head on each tool carrier having a groove arranged to receive said finger when the tool carrier is in alignment with the spindle to connect this carrier to the lever, and means for operating the lever to shift the tool carrier connected therewith toward and from the spindle.

27. In a machine of the character described, a rotatable turret, a work spindle in the turret, a support mounted forwardly of the turret to rotate therewith, a carrier pivotally mounted on the support for lateral swinging movements, a pair of laterally spaced tool carriers slidably mounted in the first carrier for movement toward and from the spindle, a pair of laterally spaced locking lugs mounted on the support, a head on each tool carrier having a groove arranged to receive one of said lugs as the first carrier is swung to shift the tool carriers out of alignment with the spindle to lock the tool carrier in its retracted position and free from the lugs when the tool carrier is in alignment with the spindle, means to swing the first carrier in timed relation with rotation of the turret to bring the tool carriers in succession into alignment with the spindle during a revolution of the turret, and means operated in timed relation with swinging movements of the first carrier to shift each tool carrier toward and from the spindle when it is in alignment with spindle and free from said lugs.

28. In a machine of the character described, a rotatable turret, a work spindle in the turret, a support mounted forwardly of the turret to rotate therewith, a sleeve mounted in the support, a carrier mounted on said sleeve, a pair of laterally spaced tool carriers mounted on the first carrier, a lever connected to the sleeve for rocking it to swing the tool carriers to and from alignment with the spindle, a stationary cam means cooperating with said lever through rotative movement of the support to swing the carrier to shift the tool carriers successively into alignment with the spindle during a rotation of the turret, and means operated in timed relation with swinging movement of the first carrier to shift the tool carriers toward and from the spindle when said carriers are in alignment with the spindle.

29. In a machine of the character described, a rotatable turret, a work spindle in the turret, a support mounted forwardly of the turret to rotate therewith, a sleeve mounted in the support, a carrier mounted on the sleeve, a pair of laterally spaced tool carriers mounted for sliding movement in the first carrier toward and from the spindle, a lever connected to the sleeve having spaced recesses therein, a stationary cam

means cooperating with the lever through rotation of the support to swing the first carrier to bring the respective tool carriers successively in alignment with the spindle during a revolution of the turret, a lever pivoted to the support, means for connecting the lever to a tool carrier when said carrier is in alignment with the spindle, means for swinging this lever to shift the tool carrier connected therewith toward and from the spindle, a locking plunger adapted to enter the recesses in the first lever to lock it with the respective tool carriers in alignment with the spindle, and means connected with the second lever to withdraw said plunger to unlock the first lever when the second lever is in its retracted position.

30. In a device of the character described, a rotatable turret, a work spindle in the turret, a support mounted forwardly of the turret to rotate therewith, a carrier mounted on the support for lateral movements, a pair of laterally spaced tool carriers mounted for sliding movement in the first carrier toward and from the spindle, means for positioning the first carrier in positions to align the respective tool carriers with the spindle during a portion of the revolution of the turret and to lock the first carrier in these positions to maintain the alignment, means for shifting the aligned tool carrier toward and from the spindle when in this position, and means operated by said latter means to unlock the first carrier when the tool carrier is shifted to its retracted position.

31. In a machine of the character described, a rotatable turret, a work spindle mounted in the turret, a support mounted forwardly of the turret to rotate therewith, a pair of laterally spaced tool carriers mounted in the support for lateral movement, means for mounting the tool carriers for sliding movement toward and from the spindle, means operated by rotation of the support to shift the carriers laterally to bring them alternately into alignment with the spindle during a revolution of the turret, and means to shift the carrier which is in alignment with the spindle toward and from the spindle while it is in this position.

32. In a machine of the character described, a rotatable turret, a work spindle mounted in the turret, a support mounted forwardly of the turret to rotate therewith, a pair of laterally spaced tool carriers, means for mounting said carriers in the support for both lateral movement and sliding movement toward and from the spindle, means operated in timed relation with rotation of the support to bring the carriers alternately into alignment with the spindle during a revolution of the turret, means for locking the unaligned carrier in retracted position rendered effective and ineffective by said lateral movements of the carriers, and means for shifting the aligned carrier toward and from the spindle.

33. In a machine of the character described, a rotatable turret, a work spindle in the turret, a support mounted forwardly of the turret to rotate therewith, a carrier mounted on the support for lateral movements, a pair of laterally spaced tool carriers mounted on the first carrier for movements toward and from a work piece in the spindle, means for locking the respective tool carriers in their retracted positions when out of alignment with the spindle, means operated in certain timed relation with rotation of the turret to shift the first carrier to bring the tool car-

riers in succession into alignment with the spindle and release them from the locking means during a revolution of the turret, and means to shift the respective carriers while so positioned to and from operative position with respect to the work piece.

34. In a machine of the character described, a rotatable turret, a work spindle mounted in the turret, a support mounted forwardly of the turret to rotate therewith, a sleeve mounted in the support, a carrier mounted on the sleeve to swing laterally, a pair of laterally spaced tool bars mounted in the carrier for sliding movement toward and from the spindle and adapted to carry tools for operating on the end of a work piece mounted in the spindle, a tool bar mounted for rocking movements in the sleeve and adapted to carry tools for operating on the sides of the work piece, means operated in certain timed relation with rotation of the turret to rock the carrier to bring the first tool bars successively into alignment with the spindle during a revolution of the turret, means for shifting the tool bar so positioned toward and from the spindle, and means operated in timed relation with operation of the first tool bars to rock the third tool bar to shift the tools carried thereby toward and from the work piece.

35. In a machine of the character described, a rotatable turret, a work spindle mounted in the turret, a support mounted forwardly of the turret to rotate therewith, a sleeve mounted in the support, a carrier mounted on the sleeve to swing laterally, a pair of laterally spaced tool bars mounted in the carrier for sliding movement toward and from the spindle and adapted to carry tools for operating on the end of a work piece mounted in the spindle, a tool bar mounted for rocking movements in the sleeve and adapted to carry tools for operating on the sides of the work piece, means operated by rotation of the support to rock the carrier to bring the tool bars carried thereby successively into alignment with the spindle, shift the tool bar so aligned toward and from the work piece, and rock the third tool bar to shift the tools carried thereby toward and from the work piece.

36. In a machine of the character described, a rotatable turret, a work spindle mounted in the turret, a support mounted forwardly of the turret to rotate therewith, a sleeve mounted in the support, a carrier mounted on the sleeve to swing laterally, a pair of laterally spaced tool bars mounted in the carrier for sliding movement toward and from the spindle and adapted to carry tools for operating on the end of a work piece mounted in the spindle, a tool bar mounted for rocking movements in the sleeve and adapted to carry tools for operating on the sides of the work piece, a stationary cam means, a lever mounted on the sleeve and cooperating with said cam means by rotation of the support to swing the carrier to bring the tool bars mounted in the carrier successively into alignment with the work piece, a second stationary cam means, means carried by the support cooperating with said latter cam means to shift the tool bar so aligned toward and from the work piece, a third stationary cam, and a lever carried by the third tool bar cooperating with the latter cam to rock said bar to swing the tools carried thereby toward and from the work piece.

37. In a machine of the character described, a rotatable turret, a work spindle mounted in the turret, a work holding chuck mounted in the spindle, means mounted on the turret for releas-

ing the chuck, a support mounted forwardly of the turret to rotate therewith, a sleeve mounted in the support, a carrier mounted on the sleeve to swing laterally, a pair of tool bars mounted in the carrier to slide toward and from a work piece in the chuck, a third tool bar mounted for rocking movements in the sleeve, a rod mounted in the third bar and extending to a position to operate the chuck releasing means, a plurality of stationary cams, and means carried by the support cooperating with respective cams by rotation of the support to swing the carrier to bring the tool bars carried thereby successively into alignment with the spindle, shift the bar so aligned toward and from the work piece, rock the third tool bar to shift the tools carried thereby toward and from the work piece, and operate said rod to release the chuck in certain timed relation with operation of the tools.

38. In a machine of the character described, a rotatable turret, a plurality of work spindles carried by the turret, a support mounted forwardly of the turret to rotate therewith, a tool holder mounted on the support associated with each spindle to operate on a work piece therein, means for operating the tool holders in certain timed relation with rotation of the turret to perform operations on the work pieces during a certain portion of the rotation of the turret and to shift them out of alignment with the work piece during another portion of said rotation to permit removal of a finished work piece from and loading of an unfinished work piece in the spindle, means located adjacent the end of the loading position of the spindles to insert the unfinished piece to a given position in the spindle, and means on the turret to control operation of said latter means in certain timed relation with rotation of the turret.

39. In a machine of the character described, a rotatable turret, a plurality of work spindles mounted in the turret, a work holding chuck in each spindle, a work support mounted forwardly of the turret to rotate therewith, a tool holder mounted on the support associated with each spindle to operate on a work piece therein, means to operate the holders in certain timed relation with rotation of the turret to perform operations on the respective work pieces during a certain portion of the rotation of the turret and to shift them out of alignment with the respective work pieces during another portion of said rotation to permit removal of a finished work piece from the chuck and loading of an unfinished work piece in the chuck, a locator in each chuck to limit insertion of the work piece therein, means for releasing the chuck during the unloading and loading operations, means located adjacent the turret in position to engage the loaded work piece and insert it into the chuck to a position against the locator before the chuck closes, and means carried by the turret to control operation of said inserting means.

40. In a machine of the character described, a rotatable turret, a plurality of work spindles mounted in the turret, a work holding chuck in each spindle, tools associated with each spindle and rotatable with the turret to perform operations on work pieces in the chucks during a certain portion of the movement of the chucks in a rotation of the turret, means to shift the tools away from the work pieces during another portion of their movement in said rotation, means for releasing the chucks during the latter portion of their movement to permit removal of the finished work piece and insertion of an unfinished

work piece, a locator in each chuck to limit movement of the work piece into the chuck, means adjacent the turret to engage the unfinished work piece and shift it into the chuck against said locator just prior to closing of the chuck, and means on the turret to control operation of said latter means.

41. In a machine of the character described, a rotatable turret, a plurality of work spindles mounted in the turret, a work holding chuck in each spindle, tools rotatable with the turret to perform work operations on work pieces in the chucks during rotation of the turret, means to release the chucks in succession during each revolution of the turret to permit removal of a finished work piece from and insertion of an unfinished work piece in each chuck, a locator in each chuck to limit inward movement of the work piece and locate it in a given position in the chuck, and means located in position to engage the unfinished work piece and shift it into the chuck to a position engaging the locator just prior to closing of the chuck.

42. In a machine of the character described, a rotatable turret, means for rotating the turret, a plurality of work spindles mounted to rotate in the turret, a work holding chuck in each spindle, tools to perform work operations on work pieces in the chucks, means to release the chucks in succession during each revolution of the turret to permit removal of a finished work piece and insertion of an unfinished work piece, fluid operated means located in position to engage the unfinished work piece and shift it to a given position in the chuck just prior to closing of the chuck, a valve controlling operation of the fluid operated means, and means carried by the turret one for each spindle and operating by movement of the turret to control operation of said valve.

43. In a machine of the character described, a rotatable turret, a plurality of work spindles mounted in the turret, a work holding chuck in each spindle, tools to perform work operations on work pieces in the chucks, means to release the chucks in succession during each revolution of the turret to permit removal of a finished work piece and insertion of an unfinished work piece, means located in position to engage the unfinished work piece and shift it to a given position in the chuck just prior to closing of the chuck comprising a cylinder, a piston in the cylinder, a finger operated by the piston to engage the work piece, a valve to supply fluid under pressure to the cylinder, and means on the turret to operate said valve.

44. In a machine of the character described, a rotatable turret, a plurality of work spindles mounted in the turret, a work holding chuck in each spindle, tools to perform work operations on the work pieces in the chucks, means to release the chucks in succession during each revolution of the turret to permit removal of a finished work piece and insertion of an unfinished work piece, means located in position to engage the unfinished work piece and shift it to a given position in the chuck just prior to closing of the chuck comprising a support, a cylinder pivotally mounted on the support, a piston in the cylinder, a finger operated by the piston to engage the work piece and shift it into the chuck, said pivot being arranged to permit the cylinder to swing to allow the finger to move laterally with rotation of the turret, a spring tending to swing the cylinder and piston in the opposite direction, a

valve to supply fluid under pressure to the cylinder, and a cam carried by the turret adjacent each spindle to operate the valve.

45. In a machine of the character described, a horizontal central shaft, supporting bearings for the shaft adjacent the opposite ends of the shaft, a turret mounted on the shaft between the bearings, a plurality of work spindles mounted in the turret and opening through the opposite sides thereof, supports mounted on the shaft one on each of the opposite sides of the turret between the turret and the respective bearings and secured to the shaft to rotate therewith, tool carriers movably mounted in each of said supports associated with each spindle to operate on work pieces in the spindles from the opposite ends thereof, means for rotating the shaft to rotate the turret and the said supports together, and means for shifting said tool carriers in certain timed relation with rotation of the turret.

46. In a machine of the character described, a horizontal central shaft, supporting bearings for the shaft adjacent the opposite ends of the shaft, a turret mounted on the shaft between the bearings, a plurality of work spindles mounted in the turret and opening through the opposite sides thereof, supports mounted on the shaft one on each of the opposite sides of the turret between the turret and the respective bearings and secured to the shaft to rotate therewith, tool carriers movably mounted in each of said supports associated with each spindle to operate on work pieces in the spindles from the opposite ends thereof, means for rotating the shaft to rotate the turret and said supports together, stationary cams, and means connected with the tool carriers and cooperating with the cams by movement of said supports to shift the tool carriers.

47. In a machine of the character described, a rotatable turret, a work spindle mounted in the turret laterally of its axis, a support mounted forwardly of the turret to rotate therewith, a carrier mounted for lateral movement in the support, a plurality of laterally spaced tool carriers mounted on the first carrier, means connected with the first carrier to shift it to move the tool carriers to and from alignment with the spindle, a stationary cam means cooperating with said latter means through rotative movement of the support to shift the first carrier to move the tool carriers successively into alignment with the spindle during a rotation of the turret, and means operated in timed relation with shifting movement of the first carrier to shift the tool carriers toward and from the spindle when said carriers are in alignment with the spindle.

48. In a machine of the character described, a rotatable turret, a work spindle mounted in the turret, a support mounted forwardly of the turret to rotate therewith, a shaft mounted in the support, a carrier mounted on said shaft, a plurality of laterally spaced tool carriers mounted on the first carrier, means for shifting the first carrier about the axis of the shaft to move the tool carriers to and from alignment with the spindle, a stationary cam means cooperating with the latter means through rotative movement of the support to shift the carrier to move the tool carriers successively into alignment with the spindle during a rotation of the turret, and means operated in timed relation with shifting movement of the first carrier to shift the tool carriers toward and from the spindle when said carriers are in alignment with the spindle.

49. In a device of the character described, a 75 rotatable turret, a work spindle mounted in the

turret, a support mounted forwardly of the turret to rotate therewith, a carrier mounted in the support for lateral movements, a plurality of laterally spaced tool carriers mounted for movements in the first carrier toward and from the spindle, means for positioning the first carrier in positions to align the respective tool carriers with the spindle during portions of the revolution of the turret, means to lock the first carrier in these positions, means for shifting the aligned tool carrier toward and from the spindle when in this position, and means controlled by the latter means to release said locking means when the tool carrier is shifted to its retracted position.

50. In a machine of the character described, a rotatable turret, a work spindle mounted in the turret, a support mounted forwardly of the turret to rotate therewith, a plurality of laterally spaced tool carriers mounted in the support for lateral movement, means for mounting the tool carriers for movement toward and from the spindle, means operated by rotation of the support to shift the carriers laterally to bring the respective carriers into alignment with the spindle during a revolution of the turret, and means to shift the carrier which is in alignment with the spindle toward and from the spindle while it is in this position.

51. In a machine of the character described, a rotatable turret, driving means for continuously rotating the turret, a work spindle mounted in the turret, means mounting a plurality of laterally spaced tool carriers in front of the turret to rotate with the turret, means mounting the tool carriers in the first mounting means for lateral movement relative to the spindle and for movement toward and from the spindle, means for positioning the respective tool carriers in alignment with the spindle during different portions of a revolution of the turret, and means to shift the aligned carrier toward and from the spindle when in this position.
